UNITED STATES PATENT OFFICE

2,428,339

SHOE BUFFING DEVICE

Frederick A. Quinn, Boston, Mass.

Application April 7, 1945, Serial No. 587,141

2 Claims. (Cl. 15—209)

1

My present invention relates to a buffing device for use in treating a coat of polish or the like applied to footwear or other leather articles to provide a neat finish.

In shining shoes, at the present time, it is the common practice first to employ a brush on the surfaces to which the polish has been applied and then to finish the polishing of the surfaces by means of a polishing cloth.

This practice is not wholly satisfactory as the brushes attack and remove a substantial part of the thin layer of polish as an incident to treating it. In addition, such brushes are relatively expensive and rather cumbersome to handle and use.

A buffing device in accordance with my invention consists of a fabric body adapted to be easily compressed. Such a body may be readily formed by winding a strip of fabric about a mandrel so that when removed therefrom a hollow cylinder results. I insert the body in a retaining casing of fabric and also insert in the casing, on opposite sides of the body, a pair of wooden or like splints which establish the sides of the device to ensure that pressures exerted on the sides of the device are evenly distributed throughout its length. The device is then completed by stitching or otherwise permanently closing the ends of the casing.

Such a device is well adapted for use in buffing a coat of polish as when the sides of the device are manually gripped, the device is compressed extending the top and bottom of the body, to provide a yieldable cushion of substantially uniform depth from the buffing surfaces established by the material from which the casing is made.

When a more complete outfit is desired, I provide a polishing or finishing member in the form of a fabric strip, of substantially the width of the buffing device, which may be wound about the device to be conveniently available. Such a polishing member may be used as a cover for the buffing device when the casing has become soiled.

In the accompanying drawings I have shown an embodiment of my invention from which its novel features and advantages will be apparent. In the drawings:

Fig. 1 is a side elevation of a buffing member in accordance with my invention.

Fig. 2 is a transverse vertical sectional view showing the cloth wound on the mandrel to establish the body.

Fig. 3 is a transverse vertical sectional view after the body has been removed from the man-

2

drel and the splints have been introduced between the body and the casing.

Fig. 4 is a transverse vertical sectional view showing the buffing member in slightly compressed condition as when used against the article being buffed, and

Fig. 5 is a transverse vertical sectional view of the combined buffing and polishing outfit.

In Fig. 2, I have indicated at 10 a body that may be conveniently formed by winding a strip 11 of cloth on a mandrel 12 from which it can be easily stripped to provide a hollow cylinder. The hollow body 10 is inserted in a casing 13 and splints 14 of wood or other suitable material 15 are inserted in the casing on opposite sides of the body 10. The casing 13 is then closed as by stitching or otherwise, so that the body 10 and splints 14 are completely encased.

When a buffing device in accordance with my 20 invention, is manually held for use, its sides are engaged and the pressure of the hand compresses the device laterally and extends it vertically as indicated in Fig. 4. As a result, the portions of the casing 13 to be used as a buffing surface are 25 extended and yieldably backed by the partially compressed body 10.

On the buffing device, I may wind a strip 15 of 30 cloth for use in polishing the buffed surface. The width of the strip 15 is preferably substantially the length of the buffing device. While the polishing strip may be readily detached for separate use, it or a like strip may be used as a cover for my device when the casing 13 has become so soiled as to be unfit for further use.

It will be understood that the buffing device 35 may be sold by itself or the polishing strip and the device may be sold as a combined buffing and polishing unit. When such a unit is to be sold, it may be packed in a suitable box or united by a 40 wrapper to prevent the unwinding of the polishing strip.

It will be apparent that buffing devices in accordance with my invention are of light weight and inexpensive construction and are well adapted 45 for use in buffing the coat of polish on shoes.

What I therefore claim and desire to secure by Letters Patent is:

1. A buffing device for footwear or other articles of leather and the like, said device comprising 50 a hollow cylindrical body of yieldable stock and of substantial length the wall of said body being of substantial thickness, a fabric casing enclosing said body, and splints longitudinally disposed in said casing along opposite outer sides of said body, said splints being of substantially the

length of said body and of substantial width and establishing zones for manual engagement by the user and being of sufficient width and length so that holding pressures applied at said zones are uniformly distributed throughout substantially the entire length of the device, said device normally having insufficient mass extending above or below said splints for effective buffing use but when held under compression at said zones a substantial portion is exposed above and below said splints and said body is sufficiently deformed to render it adapted for buffing use.

2. A buffing device for footwear or other articles of leather and the like, said device comprising a spirally wound, hollow cylindrical body of 15 fabric the wall of which is of substantial thickness, said body being of substantial length, a fabric casing enclosing said body, and splints longitudinally disposed in said casing along opposite outer sides of said body, said splints establishing zones for manual engagement by the user and being of sufficient width and substantially of the length of said body so that holding pressures applied at said zones are uniformly distributed throughout substantially the entire length of the 20 25 device, said device normally having insufficient

mass extending above or below said splints for effective buffing use but when said device is held under compression at said zones a substantial portion is exposed above and below said splints and said body is sufficiently deformed to render it adapted for buffing use.
